The ornamental design for a jet for a gas burner, as shown and described.

DESCRIPTION

FIG. 1 is a rear perspective view of a jet for a gas burner according to a first embodiment;

FIG. 2 is a front view of the jet for a gas burner shown in FIG. 1;

FIG. 3 is a rear view of the jet for a gas burner shown in FIG. 1, showing the air inlet;

FIG. 4 is a side view of the jet for a gas burner shown in FIG. 1;

FIG. 5 is a side view of the jet for a gas burner shown in FIG. 1;

FIG. 6 is a top view of the jet for a gas burner shown in FIG. 1; and,

FIG. 7 is a bottom of the jet for a gas burner shown in FIG. 1, showing the gas/air outlet.

FIG. 8 is a rear perspective view of a jet for a gas burner according to a second embodiment;

FIG. 9 is a front view of the jet for a gas burner shown in FIG. 8;

FIG. 10 is a rear view of the jet for a gas burner shown in FIG. 8, showing the air inlet;

FIG. 11 is a side view of the jet for a gas burner shown in FIG. 8;

FIG. 12 is a side view of the jet for a gas burner shown in FIG. 8;

FIG. 13 is a top view of the jet for a gas burner shown in FIG. 8; and,

FIG. 14 is a bottom of the jet for a gas burner shown in FIG. 8, showing the gas/air outlet.

FIG. 15 is a rear perspective view of a jet for a gas burner according to a third embodiment;

FIG. 16 is a front view of the jet for a gas burner shown in FIG. 15;

FIG. 17 is a rear view of the jet for a gas burner shown in FIG. 15, showing the air inlet;

FIG. 18 is a side view of the jet for a gas burner shown in FIG. 15;

FIG. 19 is a side view of the jet for a gas burner shown in FIG. 15;

FIG. 20 is a top view of the jet for a gas burner shown in FIG. 15; and,

(Continued)

FIG. 21 is a bottom of the jet for a gas burner shown in FIG. 15, showing the gas/air outlet.

FIG. 22 is a rear perspective view of a jet for a gas burner according to a fourth embodiment;

FIG. 23 is a front view of the jet for a gas burner shown in FIG. 22;

FIG. 24 is a rear view of the jet for a gas burner shown in FIG. 22, showing the air inlet;

FIG. 25 is a side view of the jet for a gas burner shown in FIG. 22;

FIG. 26 is a side view of the jet for a gas burner shown in FIG. 22;

FIG. 27 is a top view of the jet for a gas burner shown in FIG. 22; and,

FIG. 28 is a bottom of the jet for a gas burner shown in FIG. 22, showing the gas/air outlet.

The invention is an ornamental design for a jet for a gas burner having four embodiments wherein:

In embodiments 1 and 3 the inlet for gas is at the right hand side;

In embodiments 2 and 4 the inlet for gas is at the left hand side;

In embodiments 1 and 2 there are factory provided first/outer mounting holes, namely oblong holes, for mounting the jet to the gas burner;

In embodiments 3 and 4 there are factory provided first outer/mounting holes, namely round holes, for mounting the jet to the gas burner; and

The broken lines shown in the figures are for the purpose of illustrating portions of the jet for a gas burner and form no part of the claimed design.
